UNITED STATES PATENT OFFICE

ALFRED F. MCCOLLUM, OF BLOOMSBURG, PENNSYLVANIA, ASSIGNOR OF THREE.
FIFTHS TO JAMES HAGEN, SR., OF BLOOMSBURG, PENNSYLVANIA.

RUG.

1,049,119.

Specification of Letters Patent. Patented Dec. 31, 1912.
Application filed January 22, 1912. Serial No. 672,675.

To all whom it may concern:

Be it known that I, ALFRED F. MCCOLLUM, a citizen of the United States, and a resident of Bloomsburg, Columbia county, 5 Pennsylvania, have invented certain Improvements in Rugs, of which the following is a specification.

My invention consists of a turned-under edge binding for fabrics and is particularly 10 adapted for binding the cut or raw edges of carpets, rugs or other floor coverings.

One of the objects of my invention is to bind a turned-under edge of a fabric in such 15 manner that no raw edges of the fabric or binding material will be exposed along the length of the said turned-under edge.

Another object is to bind a turned-under edge so that the same will be neat and durable and will not spread or become 20 irregular.

Still another object of my invention is to 25 so arrange the stitching that the bound edges of the fabric will lie flat on the floor and will not become loose.

These and other objects and advantages 30 I attain in the following manner reference being had to the accompanying drawings in which—

Figure 1 is an inverted plan view of sufficient 35 of a rug to show one form of my improved binding. Fig. 2 is a perspective view of a portion of the bound edge shown in Fig. 1. Fig. 3 is a fragmental perspective view showing the stitches all of the 40 same length.

Referring to the drawings 1 is the body of the fabric which is shown in the present instance as a cut pile fabric having a non-pile portion 2 forming the edge thereof. 45 The portion 2 is turned so as to lie substantially parallel with the back of the body portion 1. A binding strip 4 of oil cloth or other durable material has the edge 5 interposed between the portions 1 and 2 and is folded around the end 6 of the fabric and rests against the outer face of the portion 2; the edge 7 of the binding strip being turned-in between the body portion thereof and the portion 2 of the fabric as clearly 50 shown in Figs. 2 and 3. The binding strip and fabric are held together by stitching 8.

In Fig. 1 which shows a rug made up from three sections 9, 10 and 11 and seamed at α and β , I have shown the stitches 12,

of the stitching 8, of variable lengths, said 55 stitches being long in the middle of each section and gradually becoming shorter toward the seams α and β and edges 13 and 14. The shortening of the stitches in the manner just described strengthens and 60 makes the fabric more rigid near the corners and thereby causes the same to remain flat upon the floor and also insures that the fabric is well bound at points adjacent the seams. This latter method of stitching 65 is especially valuable when binding large sectional rugs but may also be employed when making one-piece rugs. When using variable length stitches to bind a one-piece rug the said stitches can be arranged similar 70 to those binding one of the sections shown in Fig. 1 in other words the stitches are long in the middle of the rug and become shorter as they approach the selvage edges 75 of the rug.

The binding strip, by being inserted between the body and turned portion of the fabric and folded around the end 6 in the manner shown, has no raw edges exposed throughout the length thereof and supports 80 and covers the said raw end or edge 6.

In the claims I have used the term "wear material", by this is meant any tough durable material such as oilcloth, leather or the like.

While I have illustrated and described 85 my invention as applied to a cut pile rug it will be understood that the same would be serviceable in many other types of floor fabrics where a neat and durable binding is 90 desired.

I claim:

1. As a new article of manufacture, a fabric floor covering having a pile body portion and a non-pile edge portion turned 95 under the body portion, with a strip of wear material having one edge interposed between the turned under non-pile portion and the under side of the body portion of the fabric floor covering, the outer edge of said 100 strip being turned in against the face of the non-pile portion and the body of the strip extending over the face of said latter portion and around the turned under edge; and stitching securing the wear strip to the 105 fabric and the non-pile portion to the body of the fabric, said stitching also securing the in-turned outer edge of the wear strip,

2. As a new article of manufacture, a carpet rug having selvage edges and cut edges, each of said cut edges being turned under the rug; with a row of stitches securing the turned under portion to the body of the rug; said stitches being short in length 10 near the selvage edges and longer in length midway between said edges so as to firmly secure the in-turned edges to the fabric at the corners and to stiffen the corners so as to prevent them from turning up.
3. As a new article of manufacture; a carpet rug having selvage edges and cut edges, said cut edges being turned under the rug; a binding strip of wear material interposed between each turned under edge 20 and the body of the rug and folded over respective cut edges; and stitching securing each wear strip to its respective turned under edge portion and the turned under edge portion to the body of the rug, said stitches being short in length near the selvage edges and longer midway between the said selvage 25 edges so as to firmly secure the turned under edges to the body of the fabric adjacent to the corners of the rug and to stiffen the 30 corners so as to prevent them from turning up while on the floor.
4. As a new article of manufacture; a sectional carpet rug made of a series of strips having selvage edges and cut edges, said strips having their contacting selvage 35 edges seamed together by longitudinal lines of stitches and having their adjacent cut edges turned under to form an edge; a binding strip of wear material interposed between each turned under edge and the body 40 of the rug; each of said binding strips being folded over a respective turned-under cut edge; and a stitching securing each wear strip to its respective turned-under edge portion and the turned-under edge portion 45 to the body of the rug, said stitches being short in length adjacent to the points where one section is seamed to another and longer in length midway between these points and the outer selvage edges so as to firmly secure the turned-under edges to the fabric adjacent to the corners of the rug and to stiffen the corners and prevent the rug from 50 ripping at the seams.

In testimony whereof, I have signed my name to this specification, in the presence of two subscribing witnesses.

ALFRED F. McCOLLUM.
